UNITED STATES PATENT OFFICE.

GEORGE J. BOHLMAN, OF MEDFORD, MASSACHUSETTS.

PAPER RECEPTACLE.

1,192,824.

Specification of Letters Patent.

Patented July 25, 1916.

Application filed May 15, 1916. Serial No. 97,510.

To all whom it may concern:

Be it known that I, GEORGE J. BOHLMAN, a citizen of the United States, residing at Medford, in the county of Middlesex and State of Massachusetts, have invented an Improvement in Paper Receptacles, of which the following is a specification.

This invention relates to a paper receptacle primarily intended for use in transporting potted plants or the like, although readily serviceable as a convenient container for other purposes.

The invention consists in a receptacle composed of a single blank particularly formed for interlocking and securing the meeting edges of the bowl, and also providing a bottom and means for locking and supporting the bottom in place, the connection of the bottom proper and its locking and supporting means with the main body of the blank being at what are diametrically-opposed or spaced apart points of the formed receptacle, in order to provide the maximum strength at this point.

In the drawings: Figure 1 is a plan of the blank formed in accordance with the preferred construction. Fig. 2 is a side elevation and longitudinal vertical section of the pot formed from such blank. Figs. 3 and 4 are plans of blanks showing modified constructions.

In the preferred construction, shown in Figs. 1 and 2, the blank, constructed of a thick heavy paper or the like, of sufficient strength for the purpose comprises a body-portion, shaped to form the bowl of the pot when completed. For this result the body is an elongated strip 1, of sufficient length and width for the desired proportions of the completed article, having a curved upper and lower edge 2 and 3, the latter being on a less radius than the former. The side edges 4 are on lines approximately radial of a curvature intermediate that of the respective upper and lower edges. Integral with one edge is a locking strip 5 projecting therefrom and terminating in tongues 6, otherwise free of connection with the blank. The blank adjacent the opposing side edge 4 is formed with slots 7, disposed and sized to receive the tongues to lock the opposite ends of the body-portion of the blank into formed relation. The strip 5, which, together with the tongues 6, is approximately of the full width of the body portion of the blank, acts to materially reinforce the structure at the

meeting edges, also covering such juncture and preventing leakage of the contents.

The bottom edge of the blank, at such points as are diametrically opposed in the formed structure, are integrally provided with circular extensions 8, adapted to be arranged in superimposed relation in the completed article to form a double bottom. At other points, and also in diametrically-opposed relation in the completed article, the bottom edge of the body is formed with integral locking strips 9, the free terminals of which are designed to be passed through alining slots 10 in the bottoms 8, the strips being reflexed upon the top of the bottom-sections, as shown in Fig. 2, so that the reflexed portions are adapted to be held in place by the contents of the bowl, thus to securely hold the bottom-sections in place. The bottom-sections 8 and locking-strips are thus connected with the body portion at diametrically-opposed points, respectively, so that the bottom, considered as an entirety, may be said to be supported from four equally spaced points from the bowl, thus giving the maximum strength to the pot, which naturally supports the weight of the contents thereof.

In Fig. 3 one of the circular bottom pieces is omitted, both locking-strips passing through the bottom-piece remaining, and being reflexed upon the top of the bottom-piece.

In Fig. 4 the blank is slightly modified in that but a single bottom section 11, and a single locking-strip 12, therefor, is used. In this form, the connection of the bottom section and strip to the body will be at points diametrically opposed in the formed article, contributing the maximum strength to this form.

The paper of which the blank is formed is preferably of ordinary texture, untreated for its designed use, in order to permit a direct permeation of moisture to avoid accumulation in the lower portion of the pot, and to permit the ground moisture to reach the plant in the event the latter is planted while in the pot, as is contemplated among the uses of the invention.

I claim:

1. A paper pot comprising a blank having a body-portion adapted to be formed to provide the bowl of the pot, said body-portion having at its opposite ends integral interlocking-means, a bottom section integral

with the body-portion and adapted to be arranged to close the bottom of the formed bowl, and a long locking strip integral with the body and arranged to pass through the bottom-section and to be reflexed upon the top of said section to support the same in bottom-forming position, the bottom-section and locking-strip being arranged on the bottom edge of the body-portion at spaced points.

2. A paper receptacle comprising a blank having a body-portion adapted to be formed to provide the bowl of the receptacle, integral means for interlocking the meeting edges of the formed bowl, a plurality of bottom sections integral with one edge of the body-portion and adapted to be arranged in superimposed relation to form a double bottom for the bowl, the bottom sections being

secured to the edge of the body-portion at 20 points having diametrically-opposed relation in the formed article, and locking strips integral with the edge of the body portion and adapted to each interlock with both bottom sections to support the completed bottom, the respective locking strips being secured to the same edge of the body portion as the bottom sections, at spaced points therefrom, and at relatively diametrically-opposed points in the formed article.

In testimony whereof, I have signed my name to this specification, in the presence of two subscribing witnesses.

GEORGE J. BOHLMAN.
